STRUCTURAL MATERIAL AND METHOD FOR
MAKING THE SAMEAlbert H. Brunner, Los Angeles, Calif., assignor to
Schumacher Wall Board Corporation, Los
Angeles, Calif., a corporation of Delaware

Application June 8, 1934, Serial No. 729,579

8 Claims. (Cl. 154—2)

This invention relates to an improved structural material of the type generally referred to as wall board, in which a core of suitable cementitious composition is held between fibrous sheets, such as sheets of laminated paper. The invention is particularly directed toward a structural material which is incased within a fibrous covering so that both of the major surfaces of the board as well as the longitudinal edges thereof are protected by the covering.

The invention also relates to a method of making a wall board of the character stated hereinabove, in a continuous, rapid and economical manner. Moreover, the invention is directed toward a machine capable of being used with great effectiveness in carrying out the method and producing the product of this invention.

Incased wall board has been made heretofore but the fibrous coverings used have been overlapped or inserted into the cementitious material in such manner as to materially weaken the edge portions of the board or produce undesirable elevations in the board surface. Inasmuch as wall board is attached to studding by means of nails extending through the edge portions of the board, it is necessary that such edge portions be stronger and not weaker than the rest of the board. Furthermore, it is essential that the fibrous coverings be tenaciously adherent to each other and to the core as otherwise the coverings are readily torn off during handling and the usefulness of the board greatly impaired.

Generally stated, this invention contemplates a wall board comprising a cementitious core provided with a covering sheet of fibrous material in contact with one face of the core and a second sheet of fibrous material in contact with the other face of two longitudinal edges of the board, the edges of the second sheet extending into the edge portion of the first sheet or extending between laminations at the edge portions of the first sheet, such extending edge being firmly cemented between the split edge of the cover sheet.

The invention also relates, as stated hereinabove, to a particular arrangement of elements whereby a product of the character defined hereinabove may be readily manufactured, and to a method whereby the desired structure can be readily produced.

An object of this invention, therefore, is to disclose and provide an improved structural material incased in a fibrous covering.

Another object is to disclose and provide a facile and economical method of making incased wall board or similar structural material.

A further object is to disclose and provide an apparatus particularly adapted for the manufacture of improved incased wall board.

These and other objects, uses, advantages and adaptations of this invention will become apparent to those skilled in the art from the following detailed description of the finished product and of the preferred method of operation and an illustrative form of machine whereby the product can be made.

In describing the invention, reference will be had to the appended drawings, in which:

Fig. 1 is a transverse section, partly diagrammatic, through an improved form of incased wall board.

Fig. 2 is a diagrammatic side elevation, partly broken away, of a combination of elements comprising a machine for the manufacture of wall board.

Fig. 3 is a section taken along the plane III—III of Fig. 2.

Fig. 4 is a section taken along the plane IV—IV of Fig. 2.

Fig. 5 is a section taken along the plane V—V of Fig. 2.

Fig. 6 is an enlarged section taken along the plane VI—VI of Fig. 2.

Fig. 7 is a section taken along the plane VII—VII of Fig. 2.

Fig. 8 is a section taken along the plane VIII—VIII of Fig. 2.

Fig. 9 is a section taken along the plane IX—IX of Fig. 2.

As shown in Fig. 1, the board of this invention comprises a cementitious core 1, a bottom fibrous covering 2, and an upper cover sheet of fibrous material 3. The core 1 may be composed of any suitable cementitious material or filler.

Normally, gypsum compositions are employed as a core. Attention is called to the fact that the outer edges 4 and 5 of the bottom sheet 2 are beveled and are cemented into the split edges 6 and 7 respectively of the cover sheet 3. The inner surfaces of the split edges 6 and 7 are coated with an adhesive (not shown in the drawings) which tenaciously binds the beveled edges 4 and 6 with the bifurcated edges of the cover sheet 3. The edge portions 4 and 5 of the lower sheet 2 may be of any desired length so that the edges of the cover sheet 3 may either adjoin the upper corners of the finished wall board or such edges may be spaced from such corners.

As a result of the construction shown, a full thickness of cementitious material exists in the edge portions of the wall board, thereby imparting a high degree of strength and durability to the board. The adhesive used may be any suitable adhesive, such as casein, latex, or the like, which is capable of firmly bonding the edges of the cover sheet 3 to the beveled edges 4 and 6 of the bottom sheet 2. The adhesive may be applied to the inner surfaces of the split edges 6 and 7 of the cover sheet 3 by any suitable means, such as a brush, roller, or the like, or it may be applied by any other suitable means.

ing the requisite and desired strength to these sections of the board.

Attention is also called to the fact that there are no entire exposed edges of covering material protruding from the surface of the board and as a result, it is substantially impossible to rip or tear the covering from the core of the board.

Preferably, the upper covering sheet 3 is but slightly narrower than the total width of the board so that the construction described acts as a reinforcing at the edge portions, preventing shattering of the core when nails or other connecting means are driven through or attached to the edges of the board.

15 The machine diagrammatically shown in Fig. 2 is eminently suited for the continuous manufacture of the hereinabove described product, although the board can be made by the use of other instrumentalities. As shown in Fig. 2, the machine comprises a frame on which a continuous conveyor 10 is mounted. Means for driving the conveyor are provided although they are not shown in the drawings. The bottom sheet 2 of fibrous covering material is supplied from a feed roll 12 and passes through suitable trimming means for trimming the edges of the sheet to the requisite width. The trimming means may include a pair of shafts 13 and 14 carrying discs 15 and 16 respectively, the discs 15 and 16 overlapping one another in substantially sliding contact. The edges of the discs 15 and 16 are maintained sharp so that a continuous cutting action is exerted by the cooperation of said discs upon the fibrous sheet 2.

30 35 40 The upper shaft 13 and discs 15 carried thereby may be driven, although it is not necessary that the lower shaft and discs 16 be driven as the fibrous sheet 2 will cause said discs to rotate, thereby presenting a self-cleaning and new surface to the cutting action.

45 50 55 The trimmed sheet may then pass into operating contact with scoring means capable of partially cutting into the surface of the sheet for the purpose of facilitating subsequent folding of the sheet along predetermined lines. Heretofore difficulty has been experienced in forming a wall board with square and accurate edges. Attempts have been made to facilitate bending of the sheets in the formation of corners by beading the same or forming depressions therein, but such methods have not been found satisfactory. If, on the other hand, a definite groove is cut into one face of the fibrous sheet, a sufficient amount of material can thus be removed so as to insure accurate folding and the formation of a sharp corner.

60 65 70 The crimping means shown in the drawings comprise cutting wheels 17 mounted on shafts driven by motors 18. The motors may be mounted upon a suitable framework 19 and be provided with means for adjustably positioning the same with respect to the plane of the sheet 2. Such means may comprise a threaded bolt 20 having its end journaled in the motor, the body of the bolt threadedly engaging a stationary member 21 carried by the support 19. During the scoring or groove-forming operation, the sheet 2 may pass in contact with a supporting member 22 so that the paper is gently pressed against such support during the operation.

75 During scoring, one surface (preferably the inner surface of the sheet) is partially cut so as to form longitudinally extending grooves spaced a distance substantially equivalent to the width of the finished board. At the same time, additional

grooves may be formed between the edges of the sheet and the first named grooves so as to form grooves spaced from said first named grooves a distance substantially equivalent to the thickness of the finished board.

5 10 15 When desired, the sheet may then be advanced into contact with a beveling means, shown in detail in Fig. 5, for the purpose of providing the longitudinal edges of the sheet 2 with a bevel or bevel edge. The beveling devices may comprise grinding wheels 23 provided with a conical surface, mounted on shafts driven by motors 24. Means may be provided for adjustably positioning the grinding wheels with respect to the plane of the sheet, thereby regulating the extent of the bevel.

20 25 30 The sheet 2 prepared as above described is then continuously advanced by the carrier 10 into the forming portions of the machine. As shown in Fig. 6, folding guides 25 are attached to the frame of the machine in such position as to raise the edge portions of the sheet 2 and fold the same along the grooves 26 made by the scoring discs 17. The guides 25 may be adjustably positioned on the frame so as to permit adjustment when boards of varying width are being made.

35 40 45 50 55 60 65 70 75 The sheet 2 with edge portions upturned is then supplied with cementitious material 27 continuously fed to the advancing sheet 2 by means of a suitable feeding mechanism such as the conveyor 28. A cover sheet 3 from the roll 30 is then brought into contact with the cementitious material carried by the sheet 2 by means of the pinch roll 31. This cover sheet 3 may pass through trimmers 15' and 16' and preferably has its edge portions split by means of the device generally indicated at 32 (Fig. 2) and shown in greater detail in Fig. 7. It is to be understood that the cover sheet is preferably made of a laminated paper and in the preferred form of this invention the edge portions of the cover sheet 3 are split along a lamination for a distance of from about $\frac{1}{2}$ inches to $1\frac{1}{2}$ inches. During splitting, the paper is preferably retained between a stationary supporting surface 33 and a yieldable shoe 34 provided with curved ends, such shoe being yieldably pressed against the paper by means of a spring 35 positioned between said shoe and a stationary frame member 36. The splitting device itself may assume a number of forms but a self-cleaning type of splitting device consisting of a disc or polygon, has been found most effective.

80 85 90 95 100 The disc 37, for example, may be provided with a sharp beveled edge portion 38 adapted to enter the paper, the disc lying in a plane parallel to the plane of the sheet 3. The disc 37 may be driven as by the motor 39 in a direction opposed to the travel of the paper 3. The base of the motor 39 may be adjustably positioned on a stationary web 40 so that the depth to which the disc 37 penetrates the paper 3 may be regulated. In a modified form of the device, the shaft on which the disc 37 is mounted may be provided with a friction clutch on which the tension may be adjustably regulated and the disc rotated with some slippage by the advancing sheet 3 with which it is in engagement. A stationary knife-like slitting device may also be used, particularly when the operation of the machine is being initiated.

105 110 The cover sheet prepared as above described is then applied to the surface of the cementi-

tious material carried by the bottom sheet 2. In addition to the pinch roll 31, the two sheets may be more firmly compacted around the cementitious material by means of the rolls 42 and 43.

As the two sheets continue their advance, the upper sheet 3 encounters a device for separating the split longitudinal edges of the cover sheet. As shown in Fig. 8, a thin curved and polished metal plate 44 enters the previously formed split in the edge portion of the cover sheet, leaving the upper portion in the manner shown in Fig. 8, the lower portion 6' of the bifurcated edge remaining in contact with the cementitious material. While the upper edge portion of the cover sheet 3 is in its raised position, an adhesive is supplied to the inner surfaces of such bifurcated edge in any suitable manner as, for example, by means of the atomizer or spraying device 45 supplied with suitable adhesive such as sodium silicate, glue, or the like. Preferably, the inner surfaces of both the upper and lower edge portions of the sheet 3 are covered with the adhesive.

The partly prepared wall board then encounters a folding device 46 which engages the upright edge portion of the bottom sheet 2, folding the same along the previously cut score line or groove and inserting the edge of such sheet into the space between the bifurcated edges of the cover sheet 3. The element 46 is adjustably attached to the stationary framework of the machine. Immediately after such insertion, the upper edge portion of the bifurcated cover sheet 3 is forced down upon such inserted edge 4 by means of an ironing roll 50, thereby cementing the edge portion 4 within and between the split edge portion of the cover sheet 3.

The continuous sheet thus formed continues to travel until the cementitious material has set, whereupon the continuous strip may be cut into desired lengths and dried in accordance with the usual practice.

Although a specific form of apparatus and a specific sequence of operations has been described, it is to be understood that the invention is not limited thereto. The formation of the split edge portion can take place while the cover sheet 3 is in contact with cementitious material carried by the bottom sheet 2. Instead of employing a spraying device for the adhesive, brushes or other means may be used. Instead of maintaining the upper portion of the bifurcated edge of the cover sheet 3 in raised position by means of a curved metallic guide, such as the element 44, suction can be applied through suitable nozzles to the upper surface of the bifurcated edge so as to raise such edge and maintain the same in raised position during the application of adhesive and insertion of the edge 4 of the bottom sheet 2.

These and other changes, modifications and adaptations will occur to those skilled in the art. All such changes coming within the scope of the appended claims are embraced thereby.

I claim:

1. A wall board comprising a cementitious core, a sheet of fibrous material in contact with one face of said core, a second sheet of material in contact with the other face and two longitudinal edges of the core, the edges of said second sheet extending into the edge portions of the first sheet.

2. A wall board comprising a cementitious core, a sheet of laminated fibrous material in contact

with one face of said core, and a second sheet of fibrous material in contact with the other face and two longitudinal edges of the core, the edges of said second sheet extending between laminations at the edge portions of the first sheet.

3. A structural material in sheet form comprising a cementitious core, a sheet of fibrous laminated material in contact with one face of said core, and a second sheet of material in contact with the other face and two longitudinal edges of the core, the edges of said second sheet extending between laminations and cemented to edge portions of the first sheet.

4. A method of making wall board comprising continuously advancing a bottom sheet of fibrous material provided with upturned edge portions, continuously supplying cementitious material to said bottom sheet, continuously supplying a cover sheet to cover cementitious material carried by said bottom sheet, said cover sheet being provided with edge portions split in a plane substantially parallel to the plane of said sheet, and cementing longitudinal edges of said bottom sheet within the split edges of said cover sheet to form an incased finished wall board.

5. A method of making wall board comprising partially cutting into one surface of a sheet of fibrous material to form longitudinally extending grooves spaced a distance substantially equivalent to the width of the finished board, partially cutting into the surface of said sheet between said grooves and edges thereof to form grooves spaced from said first named grooves a distance substantially equivalent to the thickness of the finished board, turning up the edge portions of said sheet along said inner grooves, continuously supplying cementitious material to said sheet, continuously supplying a cover sheet to cover cementitious material carried by the first named sheet, said cover sheet being provided with edge portions split in a plane substantially parallel to the plane of said sheet, and cementing longitudinal edges of said first named sheet within the split edges of said cover sheet to form an incased finished wall board.

6. In a method of making wall board, the steps of continuously advancing a bottom sheet of fibrous material provided with upturned edge portions, continuously supplying a cementitious material to said bottom sheet, continuously splitting the longitudinal edge portions of a cover sheet along a plane substantially parallel to the plane of said cover sheet, covering the cementitious material carried by the bottom sheet with said cover sheet, and cementing the longitudinal edges of said bottom sheet between the split edges of said cover sheet to form an incased wall board.

7. In a method of making wall board, the steps of continuously advancing a bottom sheet of fibrous material provided with upturned edge portions, continuously supplying a cementitious material to said bottom sheet, continuously splitting the longitudinal edge portions of a cover sheet along a plane substantially parallel to the plane of said cover sheet, covering the cementitious material carried by the bottom sheet with said cover sheet, applying an adhesive to the inner split surfaces of said cover sheet, and inserting the edges of the bottom sheet between the split edges of said cover sheet to form an incased finished wall board.

8. In a method of manufacturing wall board, the steps of continuously advancing a bottom sheet of fibrous material provided with pairs of

longitudinally extending grooves near its edges, said pairs of grooves being spaced a distance substantially equivalent to the width of the finished board, turning up the edge portions of said sheet along inner grooves, placing a cementitious material upon said sheet while continuously advancing the same, separately continuously advancing a cover sheet of laminated fibrous ma-

terial, splitting the longitudinal edge portions of said cover sheet between laminations, and covering the cementitious material carried by the bottom sheet with said cover sheet and cementing the longitudinal edges of the bottom sheet between the split edges of the cover sheet. 5

ALBERT H. BRUNNER.
